SYSTEM FOR THE CONVERSION OF HEAT

Kurt Nesselmann, Berlin-Siemensstadt, and Edmund Altenkirch, Neuenhagen, near Berlin, Germany, assignors to Siemens-Schuckertwerke Aktiengesellschaft, Berlin-Siemensstadt, Germany, a corporation of Germany

Application December 2, 1932, Serial No. 645,484
In Germany December 8, 1931

15 Claims. (Cl. 62—118)

Our invention relates to a system for the conversion of heat in which one or more absorption apparatus of the intermittent type are employed in a special manner for increasing the efficiency 5 of systems operating with heat converters.

As it is well known in the art all refrigerating apparatus of the absorption type contain parts which take up and some which give up heat. In absorption refrigerating apparatus of the intermittent type the generator (or absorber-generator) takes up heat during the generating period, whereas the condenser (or condenser-evaporator) gives up heat. On the other hand, during the absorption period the evaporator (or condenser-evaporator) takes up heat, whereas the absorber (or absorber-generator) gives up heat. That is to say in each two successive periods, generating and absorption period, a conversion of heat takes place, i. e., a conversion of heat of a given temperature to heat of another temperature during which heat is taken up twice and given up twice.

Heat converters according to the invention are absorption refrigerating apparatus of the intermittent or continuous type, steam power plants, steam accumulators, in general all such systems in which heat of a given temperature is converted to heat of another temperature or into another form of energy. With this object in view according to the invention a system for the conversion of heat is provided in which absorption refrigerating apparatus of the intermittent type are associated with one another or with other heat converters to form a system so that parts of the apparatus are in heat exchange with one another in such a manner that on the one hand an exchange takes place between heat—which in one part of an intermittently operating absorption apparatus is liberated by condensation or absorption 35 or is taken up as heat of generation or evaporation—and on the other hand the heat which is simultaneously taken up in one part of one of the other heat converters as heat of generation or evaporation and liberated as heat of condensation or absorption. The system is preferably carried out in such a way as not to cause a heat exchange in the above-described manner between the parts of one and the same absorption apparatus of the intermittent type. The main 50 feature of such systems is to convert heat in all cases by avoiding as far as possible irreversible cycles.

The accompanying drawings forming part of this application illustrate several embodiments of our invention.

In the drawings:

Fig. 1 shows diagrammatically a system in which two refrigerating apparatus of the absorption intermittent type are in heat exchange relation with each other for the production of refrigeration;

Fig. 2 shows diagrammatically a modification of the invention in which three apparatus of the absorption intermittent type are in heat exchange for the production of live steam by waste heat;

Fig. 3 shows diagrammatically another modification in which two absorption refrigerating apparatus of the intermittent type are in heat exchange relation with each other both during the generating and absorption period for the production of refrigeration;

Fig. 4 shows diagrammatically a further modification of the invention in which an absorption apparatus of the intermittent type as heat accumulator is in heat exchange with a steam generating plant;

Fig. 5 shows a diagrammatic view of another modified form of the invention in which an absorption apparatus of the intermittent type is used as a cold accumulator;

Fig. 6 shows diagrammatically a thermal power plant operating with four absorption refrigerating apparatus of the intermittent type;

Fig. 7 illustrates in diagrammatic form another embodiment of the invention in which a continuously operating absorption refrigerating apparatus with an absorption apparatus of the intermittent type for the production of heat and refrigeration are combined;

Fig. 8 shows diagrammatically another modification of the invention in which an absorption apparatus of the intermittent type is in heat exchange with a continuous absorption apparatus for the production of refrigeration of a particularly low temperature;

Fig. 9 shows diagrammatically a system in which a continuously operating absorption refrigerating apparatus is in heat exchange with an absorption apparatus of the intermittent type serving as heat accumulator and

Fig. 10 shows diagrammatically another embodiment of the invention in which an intermittently operating absorption apparatus is in heat exchange relation with a continuous absorption apparatus.

In the first three embodiments of our invention two or more absorption apparatus of the intermittent type are in heat exchange relation with one another. In a system for the conversion of heat of this character, the heat which is

given up or taken up by one part of an intermittently operating absorption apparatus is supplied to or abstracted from a heat absorbing or heat radiating part of another refrigerant apparatus 5 of the intermittent type.

In such a system, it is possible to utilize predetermined temperature ranges by approaching as far as possible the reversible cycle of conversion for the production of heat and refrigeration 10 without being limited in this case with respect to the temperature at which the heat or cold is to be produced, as is, for instance, the case when employing absorption apparatus not in heat exchange relation with one another as a heat converter. The apparatus may be arranged in heat exchange with one another in various manners, depending upon the object in view. Absorption refrigerating apparatus of the intermittent type are so associated with one another that a heat 15 exchange takes place, when the apparatus are working simultaneously in the same operating period or when they are working in different operating periods. The absorption apparatus may be so associated with one another that they are in heat exchange relation only during the generating period. In this case a high heating temperature may be utilized for producing a greater amount of refrigeration. It is also possible to associate the apparatus with one another for an 20 exchange of heat during the absorption period. This is particularly the case when heat of low temperature is to be used for the production of heat of higher temperature. Finally, a heat exchange between apparatus is also possible during 25 the generating period as well as during the absorption period. This case may be applied to advantage when producing refrigeration of a very low temperature by utilizing a high heating temperature.

By arranging more or less apparatus in a suitable manner in heat exchange with one another it is thus possible to cover the corresponding temperature ranges in a most efficient manner depending upon the object in view.

If a predetermined maximum temperature range should be subdivided to cover a number of narrow temperature ranges, an even number (at least 6) of absorption apparatus of the intermittent type are required. This may be effected by arranging the absorption apparatus of the intermittent type in such a manner that during the generating period another number of absorption apparatus or apparatus groups are in heat exchange with one another than during the absorption period.

In carrying out the invention as shown in Fig. 1, we provided two refrigerating apparatus of the absorption intermittent type which are connected in series during their common generating period and in parallel during the absorption period. This implies that a heat exchange between the apparatus takes place during the generating period and not during the absorption period. In this embodiment absorption apparatus are employed operating with solid absorbents or adsorbents.

In Fig. 1, 1 denotes the absorber-generator of the first apparatus. It consists of an enclosure 2, an inner tube 3 and back and front bottom plates 4 and 5. These parts are welded together to form a gas-tight container. Within the whole of the generator, heat conducting cross-ribs 6 are disposed which on the one hand serve to transfer the heat as uniformly as possible to the solid absorbent contained in the absorber-gen-

erator and on the other hand to transmit the heat of absorption during the absorption period to the air-cooled outer walls of the absorber-generator. In the front bottom plate 5 a charging passage 7 is arranged through which the absorbing material, for instance, calcium chloride or strontium bromide, is introduced into the generator. In the heat conducting cross-ribs 6 are formed openings 8 through which the refrigerant passes. Within the inner tube 3 of the generator 1 an electric heating element 9 is disposed which is connected to the supply circuit consisting of the conductors 11 and 12 through a contact making clock 10. By the contact making clock the heating element 9 is energized for a predetermined space of time and deenergized for another predetermined space of time.

During the generating period the gaseous refrigerant passes from the absorber-generator 1 through a conduit 13 into a container which 20 serves as a condenser 14, whence the liquid refrigerant flows through a conduit 15 into an intermediate reservoir 16 surrounded by the insulation of the cooling chamber 24 of the refrigerator, an evaporator coil 17 being connected to 25 the container 16. The condenser 14 of the first absorption apparatus is designed in the form of an inner heating tube of the absorber-generator 18 of a second absorption refrigerating apparatus. This absorber-generator is designed in a manner 30 similar to the absorber-generator 1. The heat of condensation of the first absorption apparatus is utilized to heat the absorber-generator 18 so that during the condensation in the first absorption apparatus, the refrigerant is expelled from 35 the absorber-generator 18. The vapor refrigerant passes through a conduit 19 into an air-cooled condenser 20, from which the liquid refrigerant flows into an intermediate reservoir 21 likewise surrounded by the insulation of the cool- 40 ing chamber 24 of the refrigerator in the same manner as the reservoir 16, the reservoir 21 being associated with the corresponding evaporator coil 22. Both evaporator coils are located in a cold storage tank 23 projecting into the cooling 45 chamber 24. 25 denotes an ice container for freezing ice cubes.

At the beginning of the absorption period the heating element 9 of the absorber-generator 1 is deenergized by means of the contact making 50 clock 10. The temperature of both generator-absorbers 1 and 18 drops under the influence of the cooling air which comes into contact with the outer walls of the generator so that the pressure in both absorption apparatus is lowered, thus 55 initiating the evaporation in the evaporator coils 17 and 22 for the refrigeration. The refrigerant of both absorption apparatus now returns in opposite direction to the corresponding absorber-generators where it is reabsorbed by the absorb- 60 ent contained therein.

It is preferable to employ different absorbents with suitable refrigerants in both absorption apparatus. For instance as absorbent magnesium chloride and as refrigerant ethylamine might be 65 employed for the first absorption apparatus, whereas in the second apparatus calcium chloride as absorbent and as refrigerant ammonia.

The advantage of this system in which the absorption apparatus are in heat exchange with 70 each other lies in the fact that by arranging both absorption apparatus in series during the generating period a higher generating temperature may be applied by utilizing as far as possible reversible cycles, whereby the refrigerating capacity 75

is considerably increased in proportion to the quantity of heat required for driving off the refrigerant. This also applies particularly to such cases when the apparatus is heated by waste heat, which is available at a higher temperature than the temperature necessary for the apparatus to be heated. In this case the heat has to drop from the higher temperature level to the lower temperature level in an irreversible manner. Applying an absorption apparatus of the intermittent type according to the invention the irreversibility of the process is avoided.

To produce live steam by waste heat, three apparatus of the absorption intermittent type as disclosed in Fig. 2 operate in parallel during their common generating period and in series during the absorption period. In this case absorption apparatus are employed which operate with liquid absorbents. The absorber-generators of the absorption apparatus are designated by the numerals 111, 121 and 131. The apparatus are heated by waste steam during the generating period. The waste steam is supplied from a supply conduit 101 to the individual heating bodies 110, 120 and 130 cooperating with the respective absorber-generators through parallel connected branch conduits provided with corresponding valves 117, 127, and 137. The discharge conduits for the condensate enter a conduit 102. As a result of the heating the operating medium contained in the absorber-generator is expelled from the solution. The vaporous operating medium passes through corresponding conduits 113, 123 and 133 into the respective condenser-evaporators 114, 124, and 134 which are cooled during this interval by the water flowing through the coolers 116, 126 and 136. The conduit 103 serves to supply cooling water to the coolers, the supply being controlled by the corresponding valves 119, 129 and 139. The individual discharge conduits for the cooling water enter a common return conduit 104. By this cooling, the operating medium is condensed in the condenser-evaporators and the liquid operating medium is collected as shown in Fig. 2.

The evaporation of the operating medium expelled in the condenser-evaporators 114, 124, and 134 is effected in this embodiment by shutting off after the generating period the heat applied to the absorber-generators with the aid of the valves 117, 127 and 137 and by interrupting the supply of the cooling water to the coolers 116, 126 and 136 by means of the valves 119, 129 and 139. At the same time, devices for the transfer of heat are put into operation which transfer the heat required for the evaporation to the condenser-evaporators. The condenser-evaporator 114 has at its lower portion a heating body 115 and the latter is supplied with waste steam by opening the valve 118 which was closed during the generating period. As a result of the application of heat, the operating medium evaporates in the condenser-evaporator 114 and again returns to the weak solution in the absorber-generator 111 through a conduit 112. The vaporous operating medium is introduced below the lowest liquid level in the absorber-generator 111 with the aid of a perforated gas conduit 165. The heat developing during the absorption period is utilized to heat the condenser-evaporator 124. To this end, a closed system for the transfer of heat is available consisting of an evaporator 141 arranged in the lower part of the absorber-generator 111 and of the condenser 143 associated therewith and disposed in the lower part of the con-

denser evaporator 124. In the conduit connecting the evaporator 141 and the condenser 143 a valve 142 is provided. In this system 141, 142, and 143 for the transfer of heat, an auxiliary medium is employed in a well-known manner which evaporates in the evaporator 141 and condenses in the condenser 143. The heat of absorption transferred by this system is utilized to evaporate the operating medium in the condenser-evaporator 124, and returns through a conduit 122 and a gas 5 perforated conduit 166 to the absorber-generator 121 where it is again absorbed. A system consisting of the parts 151, 152, and 153 for the transfer of heat corresponding to the above-described system is provided in order to transfer the heat 15 of absorption developing in the absorber-generator 121 to the condenser-evaporator 134. Consequently, the operating medium also evaporates in the condenser-evaporator 134 and returns to the absorber-generator 131 through the conduit 20 132. A system 161, 162 and 163 serves to transfer the heat of absorption from the absorber-generator 131 to a steam boiler 164 employed for producing live steam. The condenser 163 of the system for the transfer of heat is arranged in 25 the lower part of said steam boiler. The steam leaves the steam boiler through the conduit provided with the valve 168. 169 is a water supply conduit for the steam boiler and 170 a drain conduit. To the top of the condenser-evaporators 30 114, 124, and 134 conduits 144, 145, and 146 provided respectively with stop valves are connected through which the apparatus are charged with the absorption solution. In order that the solvent entrained during the operation from the absorber-generator into the condenser-evaporator 35 may flow back, drain conduits 147, 148 and 149 are employed, the latter being provided with valves 154, 155 and 156 which are opened from time to time by the attendant.

The control of the valves which serve for the reversal of the periods may be effected by hand by the attendant, the valves being preferably so arranged as to be controlled by a common control member. In this manner, it is possible to 45 carry out simultaneously all reversals by means of a single handle. It is also possible to provide in the case of large systems an electric control system for the reversal of the valves. All absorber-generators and condenser-evaporators as 50 well as the steam boiler are provided in this embodiment with heat insulation.

By the arrangement shown in Fig. 2 a considerably greater difference between the heating temperature attained and the waste heat temperature is obtained with a relatively small difference between the waste heat temperature and the cooling water temperature than with absorption apparatus not in heat exchange with one another.

In the embodiment shown in Fig. 3 in which refrigeration is produced in the cooling chamber of the refrigerator, the numeral 171 denotes the absorber-generator of the first absorption apparatus, the design of which is carried out in a similar manner as the absorber-generator shown in Fig. 1. The heat supplied by a heating element 175 drives off the refrigerant from the generator and passes it into a condenser-evaporator 172 arranged above the refrigerator through a conduit 55 173. This condenser-evaporator is in direct heat-exchange relation with the absorber-generator 176 of the second absorption apparatus, since the absorber-generator 176 is located within the condenser-evaporator 172 as disclosed in Fig. 3. 60 70 75

The heat of condensation of the first absorption apparatus is consequently transferred in this case directly through the walls of the absorber-generator 176 to the solid absorbent contained in the second absorber-generator so that here the refrigerant is also driven off. The latter passes through a conduit 177 into an air-cooled condenser 178. The liquid refrigerant of the second apparatus then flows into an intermediate reservoir 179, surrounded by the insulation of the refrigerator. To the bottom of the intermediate container 179 an evaporator coil 180 is connected in the usual manner. The evaporator coil 180 is arranged in a cold storage tank projecting into the cooling chamber 181. At the end of the generating period, the heating element 175 is de-energized, thereby putting into operation a system for cooling the absorber-generator 171. This cooling system consists of a cooling jacket 183 surrounding the absorber-generator 171. From the upper part of the cooling jacket 183 a conduit 184 leads to a cooler 186 which radiates heat to the surrounding air. A conduit 187 extends from this cooler to the lower part of the cooling jacket 183. An expansion vessel 185 is connected to the rising conduit 184. This cooling system is filled with a liquid to the level as shown in the expansion vessel 185. The circulation of liquid is controlled by means of a valve 188 which is adjusted by an electromagnet 189. The heating element 175 and the electromagnet 189 are connected to the supply circuit 191, 192 through a contact making clock 190. The latter controls the system in such a manner that the valve is closed during the generating period and open during the absorption period.

As a result of the cooling during the absorption period the solid absorbent in the absorber-generator 171 is capable of reabsorbing the refrigerant. The latter evaporates now in the condenser-evaporator 172 and returns to the absorber-generator 171 through the conduit 173. The heat of absorption is abstracted from the solid absorbent contained in the absorber-generator 176 by evaporating the refrigerant in the condenser-evaporator 172. Consequently, the refrigerant also evaporates now in the evaporator 180 and returns to the absorber-generator 176. The heat of evaporation necessary for this purpose is abstracted in a well-known manner from the cooling chamber 181, thereby attaining the desired cooling effect. The absorber-generator 171 and the condenser-evaporator 172 are provided with heat insulation. By the system described in this embodiment it is possible to produce refrigeration at a very low temperature that could not be attained with absorption apparatus not in heat exchange with one another. Since further a high generating temperature may be employed similar to the first embodiment, the ratio of refrigeration produced to the heat applied, both expressed in calories, is favorable in spite of the low temperature of refrigeration.

In the above-described three embodiments the operating medium is driven off by applying heat energy to absorber-generators. Under circumstances, it is also advantageous for the reversible utilization of a certain amount of cold at a low temperature to effect the generation of the operating medium not by the heat given off by a heating device located in the absorber-generator but by the use of a source of cold; for instance by the use of carbon dioxide snow. In this case the operating medium is expelled by carrying off the heat of condensation at a temperature which

lies lower than the temperature at which the condensate evaporates during the absorption period.

By combining heat converters with refrigerating apparatus of the absorption intermittent type, the latter may be employed in a special manner as heat and cold accumulators. A convenient application of the inventive idea may be, for instance, realized by combining an intermittently operating absorption apparatus with another heat converter so that the absorption apparatus is capable of giving up heat, absorbed and stored by the absorption apparatus during the generating period, to the heat converter during the absorption period. 15

Fig. 4 illustrates an absorption apparatus of the intermittent type operating with a liquid absorbent and in heat exchange with a steam producing plant, the apparatus of the intermittent type being employed as a heat accumulator. 20

201 denotes a heat accumulator filled, for instance, with alkali liquor and insulated against the outside atmosphere. 202 is also a heat-insulated collecting vessel for condensed water vapor. This vessel is provided with a steam dome, to which a steam outlet conduit 208 is connected, the conduit being provided with a shut-off valve 209. The collecting vessel 202 forms a part of a liquid circulating system consisting of a back and forth bent conduit 203 placed in the accumulator 201 and of a diffusor 205. In the diffusor 205, a nozzle is disposed which forms one end of a conduit 206 leading from a source of steam (not shown), the conduit 206 being provided with a valve 207. The circulating system 35 consisting of the collecting vessel 202, the conduit 203 and the conduits 204 and 214 is at first filled with water to the level as shown in the vessel 202. On opening the valve 207 steam is blown into the diffusor 205, and then condensed in the condenser 203. The condensate fills up gradually the collecting vessel 202. In this case the heat of condensation is transferred to the alkali liquor contained in the container 201, thus causing water to evaporate from the alkali solution. The water vapor passes into a vessel 211 employed as condenser-evaporator through a conduit 212 connected at the upper part to the vessel 201. The vessel 211 is surrounded by a circulation jacket 215 provided with an insulating covering, an inlet conduit 216 for the cooling water being connected to the lowest part of the jacket 215. The conduit 216 leads for some distance beneath the ground water level 210 and is connected to a pump 217 which serves to force the ground water to the jacket 215. The water after having cooled the condenser-evaporator 211 and escaped from the upper part of the jacket 215 is carried off by the conduit 218. In this manner the water vapor driven off from the alkali solution is condensed in the vessel 211. 55

In order to discharge the heat accumulator 201, valve 207 is to be closed and valve 209 to be opened. The water vapor leaving the accumulator will cause a drop of pressure in the accumulating system 202, 204, 203 and, therefore, a drop in temperature takes place. After a short time the temperature of the water contained in pipe 203 becomes lower than the temperature of the solution in the absorber 201. That means that the heat flows from the alkali solution 201 to the water contained in pipe 203. As a consequence, the alkali solution in the vessel 201 begins to absorb the water vapor which is pro- 75

duced in the vessel 211. The heat necessary for developing this water vapor is delivered from the ground water 210 which is pumped with the aid of the pump 217 to the jacket of the evaporator 211 and returns through the pipe 218. The heat of absorption developed in the absorber 201 is discharged to the water in the pipe 203, thus producing water vapor in the accumulating system. After the water in the evaporator 211 is 10 evaporated and the alkali solution in the absorber 201 diluted, the discharging process is finished and the reverse process has to take place as described in the last paragraph.

In Fig. 5 is shown an embodiment of our invention as applied to an absorption refrigerating apparatus of the intermittent type in heat exchange with another absorption apparatus of the intermittent type used as cold accumulator. 221 denotes the absorber-generator of an 15 intermittently operating absorption refrigerating apparatus in which a solid absorbent, for instance, calcium chlorid is utilized.

A heating element 222 applies heat to the absorber-generator 221 and is connected to the supply circuit $\pi\gamma$ through a contact making clock 223. 224 is the air-cooled condenser of the apparatus. During the generating period the liquid refrigerant passes from the condenser 224 into an intermediate container 226 to which an evaporator 30 coil 228 placed in a cold storage tank 225 is connected.

As soon as the heating element 222 is deenergized the liquid refrigerant evaporates in the evaporator 228 which supplies cold to the storage tank 225. The vapor returns to the absorber-generator 221 where it is reabsorbed.

Although the evaporator 228 is located in the cold storage tank 225, variations of temperature in the cooling chamber occur in such an apparatus, since no refrigeration is produced at all during the heating period. In order to avoid the variations of temperature another intermittently operating absorption refrigerating apparatus is provided whose condenser-evaporator 231 40 is located in the cooling chamber, whereas its absorber-generator 230 is arranged above the refrigerator. The absorber-generator 230 is not provided with a heating element as is the case with the absorber-generator 221.

50 The last-described additional absorption apparatus 230, 231 acts as a cold accumulator. The air in the cooling chamber circulates in the direction of the arrows, as shown in Fig. 5, during the absorption period of the apparatus producing refrigeration. A baffle plate 235 divides the cooling chamber in such a manner that the circulating air passes along the condenser-evaporator 231 of the accumulator apparatus placed in the cooling chamber. The condenser-evaporator 231 is provided with outer heat radiating ribs 234. By the cooling effect brought about during the absorption period of the absorption apparatus proper, the pressure in the interior of the accumulator apparatus is decreased so that the refrigerant is expelled in the latter from the solid absorbent contained in the absorber-generator. In this case the refrigerant vapor escape into a conduit 233 through an inner perforated conduit and reaches the condenser-evaporator 231 where it is liquefied.

70 The condenser-evaporator 231 of the accumulator apparatus which has acted as condenser during the absorption period of the absorption apparatus proper now operates as evaporator 75 during the heating period of the absorption ap-

paratus proper since the temperature now rises in the cooling chamber. The condenser-evaporator 231 prevents, owing to the refrigeration produced thereby, an undue rise of temperature in the refrigerator during the generating period 5 of the apparatus proper. The air in the cooling chamber then circulates in opposite direction. Consequently, by this system the temperature in the cooling chamber is prevented from attaining too high a value during the generating 10 period of the absorption apparatus proper and from dropping to too low a value during the absorption period without consuming unnecessary cold or heat energy.

As already stated in the introduction, the heat converter combined with an intermittently operating absorption apparatus to form a system may also consist of a thermal power plant. In such combinations, it is possible to utilize great differences in temperature for producing mechanical energy in thermal power plants by approaching as far as possible the reversible transformation cycle without exposing the parts of the thermal power plant to extremely high or low temperatures. In general, it is possible to 15 associate in this case the intermittently operating apparatus with the thermal power plant in one or more points of the apparatus so as to cause a heat exchange with one another. An apparatus of the intermittent type may, for instance, be combined with a thermal power plant in such a manner that a heat exchange occurs either during the generating period of the intermittently operating apparatus or during the absorption period. In the first case heat may be, for instance, supplied by the condenser of the intermittently operating apparatus to a heat absorbing part of the thermal power plant or, for instance bleed steam, of the thermal power plant, 20 may be utilized for heating the generator of the 40 intermittently operating absorption apparatus. Should the thermal power plant be in heat exchange with the absorption apparatus during the absorption period, the absorber of the intermittently operating apparatus may be in heat exchange with a heat absorbing part; for instance with a steam generator of the thermal power plant, or the evaporator of the intermittently operating apparatus in heat exchange relation with a heat radiating portion of the power plant; 50 for instance with a condenser. In this case, for instance, a heat exchange between the absorption apparatus of the intermittent type and the power plant is also possible in two points of the absorption apparatus. Finally, it is also possible 55 to cause a heat exchange between the thermal power plant and the intermittently operating absorption apparatus during the generating period as well as during the absorption period.

Fig. 6 illustrates a plant which comprises three 60 turbines of different pressure stages. Two of the intermittently operating absorption apparatus are connected to the turbine of the highest pressure stage and the other two to the turbine of the lowest pressure stage.

The high-pressure steam generator of the plant is designated by the reference character D. To the steam generator D a superheater U is connected, from which a steam conduit 301 leads to the high-pressure turbine T₁. The exhaust steam conduit 302 of this turbine branches off at point 303. A portion of the exhaust steam passes from this point to the medium-pressure turbine T₂ through a conduit 304, whereas the remaining portion of the exhaust steam flows to 70 75

an intermediate pressure condenser C_1 through a conduit 305. The condensate flows through a conduit 309, in which a throttle valve 310 is arranged into an intermediate pressure steam generator ZW. The steam produced in the latter reaches the point 313 through a conduit 311 at which point the exhaust steam conduit 312 of the medium pressure turbine T_2 enters. The conduits 311 and 312 join at point 313, whence 10 the vapor flows into the low-pressure turbine T_3 through a conduit 314. As soon as the steam expands in the turbine T_3 it passes as exhaust heat through the conduit 315 into the condenser C_3 where it is condensed. The condensate then 15 flows through a conduit 316 into a feed pump P , which feeds the condensate back into the high-pressure steam generator D through a conduit 317, a preheater VW and a conduit 318.

The thermal cycle of the operating medium 20 of the turbines is in heat exchange in a series of points with heat radiating and heat absorbing parts of the four intermittently operating absorption apparatus, that is to say heat is imparted to the high-pressure steam generator D 25 and to the intermediate pressure steam generator ZW from the heat radiating parts of the absorption apparatus, whereas heat is abstracted from the intermediate pressure condenser C_1 and the condenser C_2 by the heat absorbing parts of 30 the absorption apparatus. The absorber-generators of the four intermittently operating absorption apparatus are designated by the reference characters A_1 , A_2 , A_3 , A_4 and the corresponding condenser-evaporators by K_1 , K_2 , K_3 , 35 K_4 . The conduits between each absorber-generator and the corresponding condenser-evaporator are designated by the numerals 321 to 324. In bringing about a heat exchange between the absorption apparatus of the intermittent type 40 and the thermal power plant, various systems for the transfer of heat are provided which transfer the heat by means of circulating liquids. For the circulation of the liquids, pumps P_1 , P_2 , P_3 , P_4 , P_5 , P_6 , P_7 , P_8 are employed. In all heat 45 radiating or heat absorbing parts of the plant either coils built in these parts or jackets surrounding these parts are provided for the transfer of heat through which the circulation of the liquid takes place. The system is so designed 50 that the absorber-generators A_1 and A_2 of the absorption apparatus in heat exchange with the high-pressure portion of the thermal power plant receive their heat of generation from a heating boiler H and that further their heat of absorption 55 is supplied to the high-pressure steam generator D. Similarly, the heat of condensation evolving in the condenser-evaporator K_1 and K_2 is supplied to the high-pressure steam generator D, whereas the heat required for the evaporation 60 is supplied to the condenser-evaporators K_1 and K_2 by the intermediate pressure condenser C_1 of the thermal power plant.

The absorber-generators A_3 and A_4 of the absorption apparatus of the intermittent type 65 heat exchange with the low-pressure portion of the thermal power plant receive their heat of generation from the condenser C_2 of the thermal power plant, whereas the heat of absorption of said absorber-generators is supplied to the intermediate pressure steam generator ZW. The heat 70 of condensation is supplied by the corresponding condenser-evaporators K_3 and K_4 to a cooler K, whereas the heat of evaporation to the condenser-evaporators K_3 and K_4 by the condenser C_2 of the thermal power plant.

To ensure a continuous operation of the heat-exchange devices, two absorption apparatus of the intermittent type are always operating together in such a manner that one apparatus has its generating period while the other has its absorption period. The liquid circulating systems which serve to transfer the heat between heat converters are periodically reversed. To this end, a series of valves designated in Fig. 6 by the reference characters V_1 , V_2 , V_3 to 10 V_{12} are employed. These valves assume alternately in a given period always the position shown in the figure or a position obtained by a rotation of 90° in a counter-clockwise direction.

In the valve position as shown in Fig. 6 the 15 absorber-generator A_1 is heated by the heating boiler H. The latter is heated by an outside source of heat 326, whereby the liquid for the transfer of heat contained therein is heated. It passes through the valve V_3 , a conduit 331 into 20 a jacket 332 surrounding the absorber-generator A_1 and thence, driven by the pump P_1 , back to the heating boiler H through the valve V_1 and a conduit 333. As a result of the heating of the absorber-generator A_1 , the operating medium 25 contained therein passes off from the solution in the form of gas and reaches the condenser-evaporator K_1 through the conduit 321. From the condenser-evaporator, the heat of condensation is supplied by the following circulation of 30 liquid to the high-pressure steam generator D. The liquid circulates, driven by the pump P_4 , through the valve V_5 , a conduit 365, a conduit 367, a conduit 366, a heating coil 357 placed in the high-pressure steam generator D, a conduit 364 and a jacket 362 surrounding the condenser-evaporator K_1 . 35

During this time the second absorption apparatus A_2 , K_2 has its absorption period. The absorber-generator A_2 in the position of valve 40 shown in Fig. 6 is, therefore, cooled by a circulating liquid which passes from the pump P_2 through a valve V_2 , a conduit 345, a conduit 336, a heating coil 337 located in the high-pressure steam generator D, a conduit 344 and through a jacket 342 surrounding the absorber-generator A_2 back into the pump P_2 .

Simultaneously heat of evaporation is supplied from the intermediate pressure condenser C_1 to the condenser-evaporator K_2 . For this transfer 50 of heat a circulating liquid is utilized which, driven by the pump P_3 , passes through the valve V_4 , a conduit 353, a cooling coil 358 located in the intermediate pressure condenser C_1 , the valve V_6 , a conduit 351 and a jacket 352 surrounding 55 the condenser-evaporator K_2 back into the pump P_3 .

The operation of both absorption apparatus in heat exchange with the low-pressure turbine T_3 is in the valve position as shown in the drawings 60 as follows:

The absorption apparatus A_3 , K_3 has its generating period, since the absorber-generator A_3 is heated by the condenser C_2 of the thermal power plant by a system in which a liquid circulates, the circulation being brought about by the pump P_7 . This system may be traced from the pump P_7 through a jacket 374 surrounding the absorber-generator A_3 , a cooling coil 373 placed in the condenser C_2 and through the valve 70 V_{11} back to the pump P_7 . The corresponding condenser-evaporator K_3 operates at the same time as a condenser. The heat of condensation passes off from the condenser to a cooler K which is, for instance, in heat exchange rela- 75

tion with a low outside temperature. The system is traced from the pump P_8 through a jacket 371 surrounding the condenser-evaporator K_3 , the valve V_7 , the cooler K , the valve V_8 back to the pump P_8 .

The fourth absorption apparatus A_4 , K_4 has its absorption period in the position of valve shown in Fig. 6. The absorber-generator A_4 is cooled by circulating liquid which transmits the heat of absorption to the intermediate pressure steam generator ZW . This liquid circulates from the pump P_8 through a jacket 375 surrounding the generator-absorber A_4 , the valve V_{10} , a heating coil 371 placed in the intermediate pressure steam generator ZW and the valve V_{12} back to the pump P_8 . During this interval the heat necessary for the evaporation is transferred from the condenser C_2 to the corresponding condenser-evaporator K_4 . To this end, a liquid circulating system which may be traced from the pump P_5 through a jacket 376 surrounding the condenser-evaporator K_4 , a cooling coil 372 placed in the condenser C_2 and the valve V_8 back to the pump P_5 .

The absorption apparatus are operated in such a manner that the generating and absorption periods have the same duration. The valves V_1 to V_{12} are rotated 90° in the counter-clock direction at the end of an operating period. By this reversal of the valves, the liquid circulating systems, in which the absorber-generators and the condenser-evaporators of the absorption apparatus of the intermittent type are in heat exchange with the heat absorbing and heat radiating parts of the thermal power plant are reversed in such a manner that the absorber-generators A_1 and A_3 now operate as absorbers and the absorber-generators A_2 and A_4 as generators. Accordingly, the liquid circulating systems of the condenser-evaporators with the valves in the reversed position are connected in such a manner that the condenser-evaporators K_1 and K_3 now operate as evaporators and the condenser-evaporators K_2 and K_4 as condensers.

Without further tracing the liquid circulating systems for this valve position, it will be apparent from the drawings that the absorber-generator A_2 in the new valve position receives its heat of generation from the heating coil H . The condenser-evaporator K_2 transfers the heat of condensation to the high-pressure steam generator D . The absorber-generator A_1 transmits its heat of absorption to the high-pressure steam generator D and the condenser-evaporator K_1 receives the necessary heat of evaporation from the intermediate pressure condenser C_1 . The absorber-generator A_3 transfers its heat of absorption to the intermediate pressure steam generator ZW . The corresponding condenser-evaporator K_3 receives its heat of evaporation from the condenser C_2 ; finally the absorber-generator A_4 receives the heat of generation from the condenser C_2 and the corresponding condenser K_2 transfers the heat of condensation to the cooler K .

As operating medium for the thermal power plant, water vapor might be utilized. Both heat converters operating within the lower temperature range (absorption apparatus of the intermittent type A_3 , K_3 and A_4 , K_4) may be, for instance, operated with a solution of ammonia and water, whereas the heat converters operating within the higher temperature range (absorption apparatus of the intermittent type A_1 , K_1 and A_2 , K_2) may be operated with aqueous sodium hy-

dioxide solution. In the system for the transfer of heat brine may be, for instance, employed for the lower temperature range, whereas for the higher temperature range oils of high boiling point, for instance, paraffin oil, are employed to advantage. The expansion vessels designated by the numerals 381 . . . 384 are connected to the highest points of the four systems for the transfer of heat.

In the systems shown in Figs. 2 and 6 intermittent absorption refrigerating apparatus are also employed, the operation of which differs in principle from that of the usual intermittent absorption refrigerating apparatus. In the latter the generator-absorber is heated by a heat source (for instance an electric heating element) during the generating period, whereas the condenser is in heat contact with a cooling medium. During this period a high pressure prevails in the apparatus hitherto employed. During the absorption period the evaporator is in heat contact with the cooling chamber air. This air serves as a heat source, whereas the generator-absorber is in heat exchange relation with the cooling medium so that the latter takes up heat from the generator-absorber. During this period the lower pressure prevails in the known apparatus.

In contradistinction thereto intermittent absorption apparatus are employed in the systems disclosed in Figs. 2 and 6 in which apparatus the lower pressure prevails during the generating period and the higher pressure during the absorption period. The generating process is then brought about by bringing the condenser-evaporator in heat contact with the cooling medium of lower temperature, whereas the generator-absorber is in heat exchange relation with a heat source of mean temperature. Under these operating conditions, the refrigerant taken up by the absorbent evaporates, passes into the condenser and is liquefied therein. During the absorption period the condenser-evaporator is brought into heat-exchange relation with the heat source of the mean temperature and the generator-absorber then forms a heat source of high temperature.

The purpose of the system disclosed in Fig. 6 is to attain as far as possible a reversible utilization of heat of very high temperature which is produced in the heating boiler H and the utilization of the cooling effect of an available low surrounding temperature in the cooler K . In this case, it is of a particular advantage that the high temperature of the medium heated by the heating vessel H or of the media operating in the absorption apparatus do not come into contact with the steam power engines. A further advantage lies in the fact that the steam need not be expanded to the pressure corresponding to the low surrounding temperature, which cannot be effected economically owing to the very large volumes of steam. It is, consequently, possible in the above-described manner to utilize predetermined differences in temperature of very high value in an approximately reversible manner, so that the temperature of the operating medium does not reach the limit temperatures.

Finally, absorption apparatus of the intermittent type may be applied to advantage also in combination with continuously operating apparatus for carrying out a conversion of heat in various manner. In Figs. 7 to 10 are illustrated four embodiments of the invention in a diagrammatic form for the above sphere of application.

Fig. 7 shows the combination of a continuously operating absorption refrigerating apparatus with an absorption apparatus of the intermittent type for the transfer of heat and the production of refrigeration. 401 denotes the absorber-generator of an intermittently operating absorption refrigerating apparatus which operates with a liquid refrigerant. The heating of the absorber-generator is effected by a heating element 402. During the generating period the ammonia vapor reaches a vessel 404 serving as condenser through a conduit 403 connected to the top of the absorber-generator, an intermediate vessel 439 and a conduit 440. The condenser 404 is surrounded by a cooling jacket 405 which is connected through circulation conduits 406 and 407 with a heating body 408 located in the heat insulated generator 421 of the continuously operating absorption apparatus to form a closed system for the transfer of heat. In this system a liquid is contained which upon taking up the heat of condensation of the intermittently operating apparatus evaporates in the lower part 405 and is again condensed by the radiation of heat in the upper part 408. In this manner the heat of condensation of the intermittently operating apparatus is utilized for heating the generator 421 of the continuously operating apparatus. The refrigerant of the apparatus of the intermittent absorption type flows from the condenser 404 through a conduit 448 connected to the lower part thereof into an evaporator 449, where it is collected.

As a result of this heating the refrigerant is driven off from the rich solution contained in the generator 421. The refrigerant vapor passes through a percolator pipe 423 together with the weak solution raised by the refrigerant vapor into the heat insulated gas separating chamber 424, where the refrigerant vapor is separated from the weak solution. The refrigerant vapor then passes through the conduit 425 into a condenser 426 where it is condensed, the condenser 426 being arranged in an air shaft 412. The liquid refrigerant flows through a conduit 427 into the evaporator 431 which is placed in another air shaft 413. The conduit 427 leading from the condenser 426 to the evaporator 431 has the form of a U-shaped conduit, whose descending portion is connected to the bottom of the condenser 426 and whose rising portion 429 is enlarged before entering the evaporator 431 to a branch vessel 430. The latter is in turn connected to the lowest point of the conduit leading from the condenser through a U-shaped conduit 428. The U-shaped conduit system provides for a difference in pressure between the condenser and the evaporator.

The vaporous refrigerant passes through a conduit 432 into the lower part of an absorber 433 in which the weak solution from the gas separating chamber 424 and passing through the U-shaped conduit 434 flows downwardly in opposite direction to the vaporous refrigerant. Here the refrigerant is reabsorbed by the weak solution and the rich solution flows from the bottom of the absorber through the conduit 435, the heat exchanger 441 and a conduit 441a into a heat-insulated storage tank 436 and thence passes through a U-shaped conduit 437 back into the generator 421.

The heat exchanger 441 is disposed on the one hand in the conduit 435 leading from the absorber 433 to the storage vessel 436 and on the other hand in the conduit 434 leading from the gas separating chamber 424 to the absorber 433 is

a pressure equalizing conduit between the gas separating chamber 424 and the storage vessel 436.

At the end of the generating period of the intermittently operating absorption apparatus 5 the electric heating element 402 is deenergized. In order to carry off the heat of absorption the absorber-generator 401 is surrounded by a cooling jacket 409 in the upper part of which a circulation conduit 442 is connected which leads 10 through a valve 410 to the upper part of a return cooler 411 arranged in the air shaft 412. From the lowest end of the return cooler 411 a conduit 443 extends to the lowest point of the jacket 409. In this closed circulating system a 15 liquid is contained which evaporates upon taking up the heat of absorption of the absorber-generator 401 and which is cooled by the air rising in the air shaft 412. This system for the transfer of heat is put into operation at the beginning 20 of the absorption period by opening the valve 410. For actuating the valve 410 an electromagnet 444 is provided which is connected to the supply circuit 446, 447 in parallel relation with the heating element 402 through a contact making 25 clock 445. The system for the transfer of heat 405, 406, 407, 408, which heats the generator of the continuously operating absorption apparatus during the generating period of the intermittently operating absorption apparatus is not 30 in operation during the absorption period. Consequently, an electric heating element 422 arranged in the generator 421 must be energized if an uninterrupted operation of the continuous absorption apparatus is to be maintained. The 35 heating element 422 is, therefore, also connected in parallel relation with the heating element 402 and the magnet 444 to the contact making clock 445.

Owing to the cooling down of the absorber-generator 401 the pressure decreases in the intermittently operating absorption apparatus so that the liquid refrigerant evaporates again in the evaporator 449 and from which it returns to the intermediate vessel 439 through the conduit 448, 45 the condenser 404 and the conduit 440. From the intermediate vessel 439 the vaporous refrigerant is introduced into the weak absorption solution contained in the absorber-generator 401 through the conduit 450. The evaporator 449 is 50 also provided with a jacket 414 similar to that of the condenser 404. The jacket 414 is connected with a heat-transfer apparatus 415 disposed in the air shaft 413 through circulation conduits 451, 452 to form a closed system for the 55 transfer of heat. By this system the heat of evaporation of the absorption apparatus of the intermittent type is abstracted from the air flowing in the shaft 413 during the absorption period. In order to avoid losses of heat or refrigeration 60 the vessels 404 and 449 are heat insulated. The evaporator 449 of the intermittently operating absorption apparatus is so designed that the liquid solvent entrained into the evaporator during the generating period flows automatically 65 again into the absorber-generator 401. To this end, partitions 453 and 454 are arranged in the evaporator 449 which conduct the liquid refrigerant in a given direction through the evaporator vessel 449. The upper partitions 453 are provided with openings 455 through which the refrigerant vapor flows during the evaporation. The solvent entrained into the evaporator is gradually forced towards the outlet of the conduit 456 by the liquid refrigerant flowing into the 75

evaporator during the generating period and then back to the absorber generator 401 through the conduit 456.

In the air shaft 412 are located only apparatus parts 411, 426, 433 which give up heat to the air. In this shaft a hot current of air flows in the direction of the arrow. The shaft 413 contains only apparatus parts 415, 431 which abstract heat from the air flowing in this shaft. Here a cold current of air consequently flows in the direction of the arrow. The corresponding apparatus may be employed accordingly, both for heating and for refrigerating purposes.

The advantage of such a plant over a continuous absorption apparatus whose generator is directly heated consists in the fact that additional refrigeration and additional heat may be produced without increasing the heat to be expended.

Instead of the heating element 422 a heating body disposed in a second intermittently operating absorption apparatus may be arranged in a similar way as the heating body 408. The first mentioned heating body provided for heating the generator, whereas the apparatus of the absorption intermittent type connected to the heating body 408 produces refrigeration. Both absorption apparatus of the intermittent type required in this case must be accordingly so operated that their operating periods are timely displaced, that is to say one apparatus has its generating period while the other operates during the absorption period and reversely.

Fig. 8 shows an absorption apparatus of the intermittent type in heat exchange with a continuous absorption apparatus in two points of the absorption apparatus of the intermittent type for the production of refrigeration of two different temperatures, one of which is particularly low. The continuously operating apparatus contains ammonia as refrigerant and water as solvent. The reference characters in Fig. 8 are the same as those in Fig. 7 as far as like apparatus parts are concerned. 460 denotes the absorber-generator of the absorption apparatus of the intermittent type. It is filled with a solid absorbent, for instance, strontium bromide, saturated with ammonia. During the generating period the absorber-generator 460 is heated by means of the heating element 461. Thereby the ammonia is driven off from the chemical compound. It passes into a heat insulated condenser 463 through the conduit 462. The condenser 463 is in heat exchange with the generator 421 of the continuous absorption apparatus through a system for the transfer of heat. The latter consists of an evaporator 464 located in the condenser-evaporator 463 and of a condenser 465 disposed in the generator 421. The conduit connecting the generator 421 and the condenser-evaporator 463 is provided with a valve 466 which is open during the generating period of the intermittently operating absorption apparatus and closed during the absorption period. By this system the heat of condensation is transferred from the condenser-evaporator 463 to the generator 421 by alternate evaporation in the evaporator 464 and subsequent condensation in the condenser 465. Besides this exchange of heat between the last two mentioned parts, there also exists another system for the transfer of heat between both apparatus. The absorber-generator 460 of the absorption apparatus of the intermittent type is surrounded by a cooling jacket 467 which is connected with a condenser 468 ar-

ranged in the evaporator 431 of the continuous absorption apparatus through two circulation conduits 469, 470. A valve 471 arranged in the circulation conduit 470 is closed during the generating period and brought to an open position 5 during the absorption period. By the medium circulating in the above-described system for the transfer of heat, the absorber-generator of the intermittently operating absorption apparatus is cooled by the evaporator 431 of the continuous 10 absorption apparatus. From the evaporator 472 of the continuous absorption apparatus the refrigeration produced by the continuous absorption apparatus is transferred to the cooling chamber 474 by a system for the transfer of heat which 15 consists of an evaporator 473 located in the cooling chamber 474 and of a condenser 475 disposed in the evaporator 472 being connected by two circulation conduits 476, 477. The refrigeration produced by the condenser-evaporator 20 463 of the absorption apparatus of the intermittent type is transferred to another cooling chamber 480 by means of a similar transfer system 478, 479.

The embodiment shown in Fig. 7 differs from 25 the continuous absorption apparatus in that the latter in the present case operates with an admixture of an inert gas in the evaporator and absorber. The evaporator 472 forms with the absorber 433 together with two gas circulating 30 conduits 481, 482 a system in which the gas mixture circulates in the direction of the arrow in a well-known manner. To cause a circulation of gas mixture refrigerant vapor is employed 35 which is supplied to a nozzle 484 through a conduit 483 which is branched off the conduit 425.

Since the temperature of absorption of the intermittently operating absorption apparatus is low owing to the transfer of heat from the evaporator 472 of the continuous operating apparatus, 40 refrigeration of relatively lower temperature is produced as compared to the temperature prevailing in the evaporator 472 of the continuous absorption apparatus. Accordingly, the temperature of the cold transferred to the cooling chamber 480 is particularly low. 45

In the system shown in Fig. 9 an absorption apparatus of the intermittent type is employed as heat accumulator in connection with a continuous absorption apparatus.

In a heat-insulated generator 501, heated by an electric heating element 502 a rich solution, for instance, an aqueous sodium hydroxide solution, is contained therein, from which the water is driven off by application of heat. The water vapor thus expelled raises the hot solution through a small percolator pipe 503 to a gas separating chamber 504, where the absorption solution is separated from the vapor. The solution flows from the gas separating chamber 504 through a U-shaped conduit 505 into the upper part of the absorber 506 in which the solution trickles downwardly over baffle plates 507 arranged therein. The refrigerant vapor is supplied from the gas separator 504 through a conduit 508, in which an intermediate vessel 509 is inserted to an air-cooled condenser 510 designed in the form of a coil and connected by a conduit 511 with a small vapor separator 512. A U-shaped return conduit 513 leading from the vapor separator 512 to the lowest part of the condenser 510 provides for a column of liquid refrigerant in the conduit 511. The liquid refrigerant passes from the container 512 through a conduit 514 into the evaporator 515 which is pro- 75

vided inside with baffle plates and outside with ribs 517. A connecting pipe 518 conveys the refrigerant vapor from the lower part of the evaporator 515 to the absorber 506 where it is taken up by the weak absorption solution trickling downwardly. The absorber 506 is provided outside with cooling ribs 519 which assist the dissipation of heat of absorption to the surrounding atmosphere. The enriched absorption solution flows back to the generator 501 through a U-shaped liquid conduit 521 connected to the pipe 518 and being in heat exchange with the U-shaped conduit 505. Within the absorber 506 extends in the central portion thereof a liquid collecting vessel 520 which projects for some distance above the absorber and forms the condenser-evaporator of an intermittently operating absorption apparatus. The walls thereof consist of a metal which has a good heat conductivity. 522 denotes the absorber-generator of the absorption apparatus of the intermittent type. It consists of a pressure-tight container which is formed by a tubular outer jacket 523, the bottom plates 524 and 525 being welded thereto. The interior of the generator is traversed by a gas perforated conduit 526 to which heat conducting cross-ribs 527 are connected which are also in a good heat conducting contact relation with the interior walls of the absorber-generator. The cells formed by the cross-ribs are filled with a solid absorbent, for instance calcium chlorid, which is saturated with ammonia as operating medium. In order to heat the absorber-generator, a liquid system is employed which consists of a jacket 528 surrounding the absorber-generator, a coil 529 wound around the heating element 502 of the generator 501, and of two conduits 530 and 531. An expansion vessel 533 is connected to the highest point of the circulating system through a conduit 532. A conduit 534 leading to the upper portion of the condenser-evaporator 520 is connected to the perforated conduit 526 of the generator. 45 The heat is stored up in the following manner: The generator 501 is heated, on the one hand, by the heating element 502 so that the continuous absorption apparatus is put into operation, and at the same time the circulating liquid contained 50 in the coil 529 is heated so that the liquid begins to circulate and heats the absorber-generator 522 indirectly. Consequently, the operating medium passes off from the chemical compound contained 55 in the absorber 506 and reaches the condenser-evaporator 520 provided with cooling ribs 535 through the conduit 534. By the cooling effect of the air the operating medium is condensed and collects in the lower part of the condenser-evaporator. 60 Since the temperature inside the generator 506 is relatively high as a result of heat of absorption developed a portion of the liquid operating medium evaporates again in the lower part of the condenser-evaporator 520 surrounded by the absorber 506. The vapor condenses again in the upper air-cooled portion of the condenser-evaporator 520. In this manner the heat of absorption of the absorber is partly given up indirectly by means of the operating medium with the aid 65 of the ribs 535 and partly directly by the ribs 519 as long as the heating element of the generator 501 is energized. The absorber is thereby maintained to the temperature which is necessary to absorb the water vapor coming from the evaporator 515.

The electric heating element of the generator 501 is energized until the operating medium is driven off from the generator-absorber 522 and collected in the condenser-evaporator 520 as liquid operating medium. As soon as the heating 5 element of the generator 501 of the continuous absorption apparatus is deenergized, the circulation of liquid between the coil 529 and the jacket of the absorber-generator 522 is brought gradually to rest, so that no more ammonia vapor is 10 driven off from the absorber-generator 522. The operating medium contained in the condenser-evaporator 520 diminishes gradually by evaporating slowly, owing to the heat of absorption taken up from the absorber 506 of the continuous absorption apparatus. The ammonia vapor flows back through the conduit 534 to the absorber-generator 522 where it is reabsorbed. The heat resulting from this absorption is given up to the circulating liquid contained in the jacket 528 so 15 that the liquid now circulates in the opposite direction, thus heating indirectly the rich solution contained in the generator 501. In this manner, the development of the refrigerant vapor in the continuous absorption apparatus will not be interrupted, notwithstanding that the heating element 502 is deenergized. Accordingly, the condenser 510 is further charged with refrigerant vapor and the evaporator with liquid refrigerant. The production of refrigeration is, therefore, also 20 continued as long as the heat required for the generation is evolved by the absorption of fresh quantities of ammonia vapor in the absorber-generator 522.

In the above-described manner, the periods of 35 the heat storage (and of the application of heat to the generator 501 by means of the heating element 502) and the periods of regeneration of heat (and of the application of heat to the generator 501 by means of the coil 529) alternate continuously with each other.

In the system shown in Fig. 10 an intermittently operating absorption apparatus is in heat exchange with a continuous absorption apparatus, whereby the storing up of energy of intermittently operating absorption apparatus is utilized in a special manner for the operation of a continuous absorption apparatus in a similar manner as in the preceding embodiment. In this case, a system for the direct heating of the generator is 50 provided only for the absorber-generator of the absorption apparatus of the intermittent type but not for the generator of the continuous apparatus. The operation of this system is as follows:

During the generation period the heating element 602 of the absorber-generator 601 of the intermittently operating absorption apparatus is energized. The operating medium thereby passes off from the absorber-generator 601 in the form of gas through a conduit 603 and is liquefied in 60 the condenser-evaporator 604. The heat of condensation is utilized to heat indirectly during this period the generator 605, 606 of the continuous absorption apparatus. To this end, a system for the transfer of heat consisting of a heat absorbing body 607 located in the condenser-evaporator 604 and of a heating body 608 disposed in the generator 606 is provided. The conduit connecting these two parts 607 and 608 is provided with a valve 609 which during the generating period of 65 the absorption apparatus of the intermittent type is brought to the position as shown in Fig. 10. The conduit between the parts 607 and 608 of the system for the transfer of heat is partly designed as a heat transfer coil 610 which is in heat 70 75

exchange relation with the percolator coil 605 which forms a part of the conduit 612 leading from the absorber 601 to the generator 606. The liquid operating in the transfer system 607, 608, 5 610 heats the liquid in the coil 605 so that gas bubbles are developed therein which convey the rich solution to the gas separator 606 in which a further generation takes place owing to the heat evolved by the heating body 608.

- 10 During the absorption period, the heating element 602 is deenergized and the valve 609 is rotated 90° in the clockwise direction. In this manner a cooling jacket 613 surrounding the absorber-generator 601 is inserted in the system for 15 the transfer of heat instead of the cooler 607 located in the condenser-evaporator 604 so that the solution passing into the gas separator is heated, as was previously the case with the heat of condensation, by the heat of absorption.
- 20 The circulation of the refrigerant in the continuous absorption apparatus takes place as follows:

The vaporous refrigerant expelled in the coil 605 and in the gas separating chamber 606 25 reaches through a rectifier 628 and a conduit 614 the water-cooled condenser 615 where it is liquefied. The liquid refrigerant flows from the condenser 615 through a conduit 616 into the evaporator 617. Between the latter and the 30 equally water-cooled absorber 611 two conduits 618, 619 are provided, in which the inert gas circulates in order to convey the vaporous refrigerant from the evaporator 617 to the absorber 611. The conduits 618, 619 may be in heat 35 exchange with one another. The rich solution then returns in the above-described manner from the absorber 611 to the gas separating chamber 606 through the conduit 612 connected to bottom of the absorber 611. In order to cool the absorber 611 and the condenser 615 water is used 40 which flows from a conduit 620 through a cooling jacket 621 surrounding the absorber 611 and thence through a conduit 622 to the container 623 in which the condenser 615 is disposed, whence the water passes through a conduit 624 45 into a coil 625. The latter is in heat exchange relation with another coil 626 which forms together with a heat-transfer body 627 arranged in the condenser-evaporator 604 a closed system for the transfer of heat. The liquid contained 50 in this system is heated by the cooling water and thereby caused to circulate. In this case, the heat supplied to the condenser-evaporator 604 during the absorption period serves to evaporate the liquid operating medium.

55 The advantage of this embodiment of our invention consists in the fact that the generator of the continuous absorption apparatus needs no direct heating. To heat the same, the heat of condensation and of absorption of the intermittently operating apparatus is alternately utilized which must be heated only during the generating periods. Such an operation is, for instance, of particular advantage if in operating the system for the production of refrigeration 60 electricity is available at low rates during the night, without interrupting, however, the production of refrigeration.

In case a continuous absorption apparatus and an intermittently operating absorption apparatus 70 are employed in the same system for the production of refrigeration the system may be so designed that the continuous absorption apparatus serves to supply refrigeration during the generating period to the refrigeration cabinet which

is cooled by the intermittently operating absorption apparatus during the absorption period. Also by means of such a system, it is possible, similarly as in the case of the system shown in Fig. 5, to compensate for variations of temperature in the cooling chamber, which result from the operation of an absorption apparatus of the intermittently operating type. Finally, it is also possible to combine in a system a continuous absorption apparatus and an absorption 10 apparatus of the intermittent type in such a manner that a periodically increased production of refrigeration required for a refrigeration cabinet which is cooled by means of the continuous absorption apparatus is effected by the intermittently operating absorption apparatus during the absorption period.

In all the above-described embodiments are shown intermittently operating absorption apparatus in which a vaporous refrigerant is condensed and the liquid refrigerant is again evaporated. Intermittently operating absorption apparatus may also be employed in which the operating medium is liquefied in a solid or liquid absorbing medium from which it is again evaporated during the absorption period. Instead of continuous absorption apparatus, in which the operating medium is liquefied in the condenser, resorber apparatus may be employed, in which the operating medium is liquefied in a solution, 20 from which it is again evaporated without departing from the spirit and scope of the invention.

We claim as our invention:—

1. In a system in which a thermal power plant 35 is associated with an intermittently operating absorption apparatus, comprising a generator and absorber, means for heating said generator during the generating period by the steam of the power plant, said means being so arranged as to condense during the heating period the steam of the thermal power plant, said absorber being so arranged that it gives up its heat of absorption to the condensate of the thermal power plant to evaporate the condensate. 45

2. In a system for the conversion of heat, comprising several heat converters at least two of which being intermittent absorption apparatus operating with different absorbents and working media and another being a thermal power plant, 50 each having a unit in which the vaporous operating medium passes from the vaporous state to another state of aggregation and an operating medium vapor developing unit, heat-exchange means between said absorption apparatus and said plant, said means being so arranged as to cause the heat liberated in the first-named unit of one of said converters to be supplied to the last-named unit of the other of said converters for the development of the operating medium 55 vapor. 60

3. In a system for the conversion of heat, comprising several heat converters at least one of which being an intermittent absorption apparatus and another being a thermal power plant, the 65 absorption apparatus of the intermittent type comprising an absorber-generator and a condenser, means for heating said absorber-generator, and means for giving up the heat of condensation developed in said condenser to a heat absorbing part of the thermal power plant. 70

4. In a system for the conversion of heat, comprising several heat converters at least one of which being an intermittent absorption apparatus and another being a thermal power plant, the 75

- absorption apparatus of the intermittent type comprising an absorber-generator and a condenser-evaporator, means for heating said absorber-generator, said means consisting of a 5 heat-transfer device which causes a heat-exchange between a heat radiating part of the thermal power plant and the absorber-generator, and means for cooling said condenser-evaporator by dissipation of heat to the surrounding air.
- 10 5. In a system for the conversion of heat, comprising several heat converters at least one of which being an intermittent absorption apparatus and another being a thermal power plant, the intermittently operating absorption apparatus 15 comprising a generator-absorber and an evaporator, means for cooling said absorber consisting of a device which causes a heat exchange between said generator-absorber and a heat absorbing part of the thermal power plant, said evaporator 20 being so arranged that it abstracts heat from the surrounding air.
6. In a system for the conversion of heat, comprising several heat converters at least one of which being an intermittent absorption apparatus 25 and another being a thermal power plant, the absorption apparatus of the intermittent type comprising a generator-absorber and an evaporator, said evaporator being in heat exchange with a heat radiating part of the thermal power plant 30 by means of a heat exchange device, and said generator-absorber being in heat exchange with a heat absorbing part of the thermal power plant by means of a second heat exchange device.
7. In a system for the conversion of heat, comprising several heat converters at least one of which being an intermittent absorption apparatus and another being a thermal power plant, the absorption apparatus of the intermittent type 35 comprising a generator-absorber, a condenser and an evaporator, said heat-exchange means comprising a device which causes a heat exchange during the generating period between said condenser and a heat absorbing part of the thermal power plant, heat at higher temperature being supplied by a heating device during this time to 40 said generator-absorber, and a second device which causes during the absorption period a heat exchange between said evaporator and a heat radiating part of the thermal power plant.
- 50 8. In a system for the conversion of heat, comprising several heat converters at least one of which being an intermittent absorption apparatus and another being a thermal power plant, the absorption apparatus of the intermittent type comprising a generator-absorber, a condenser 45 and an evaporator, said heat exchange means comprising a device which causes a heat exchange between said condenser and a heat absorbing part of the thermal power plant during the generating period, heat at higher temperature being supplied by means of a heating device to said generator-absorber, and a device which causes a heat exchange 55 during the absorption period between said generator and a heat absorbing part of the thermal power plant.
- 60 9. In a system for the conversion of heat, comprising several heat converters at least one of which being an intermittent absorption apparatus and another being a thermal power plant, the absorption apparatus of the intermittent type comprising a generator-absorber, a condenser 65 and an evaporator, said heat exchange means comprising a device which causes a heat exchange during the generating period between said generator-absorber and a heat radiating part of the thermal power plant.
- 70 10. In a system for the conversion of heat, comprising several heat converters at least one of which being an intermittent absorption apparatus and another being a thermal power plant, the absorption apparatus of the intermittent type comprising a generator-absorber, a condenser 75 and an evaporator, said heat exchange means comprising a device which causes a heat exchange during the generating period between said generator-absorber and a heat radiating part of the thermal power plant, said condenser being so arranged that it is cooled during this time by the surrounding air, and a device which causes a heat exchange during the absorption period between said generator-absorber and a heat-absorbing part of the thermal power plant.
11. In a system for the conversion of heat, comprising several heat converters at least one of which being an intermittent absorption apparatus and another being a thermal power plant, the absorption apparatus of the intermittent type comprising a generator-absorber, a condenser and an evaporator, said heat-exchange means comprising a device which causes a heat exchange during the generating period between said condenser and a heat absorbing part of the thermal power plant, heat of higher temperature being supplied by means of a heating device to said generator-absorber, a device which causes a heat exchange during the absorption period between said evaporator and a heat radiating part of the thermal power plant, and a device which causes a heat exchange during the absorption period between said generator-absorber and a heat absorbing part of the thermal power plant.
12. In a system for the conversion of heat, comprising several heat converters at least one of which being an intermittent absorption apparatus and another being a thermal power plant, the absorption apparatus of the intermittent type comprising a generator-absorber, a condenser and an evaporator, said heat-exchange means comprising a device which causes a heat exchange during the generating period between said generator-absorber and a heat radiating part of the thermal power plant, said condenser being so arranged that it is cooled during this time by the surrounding air, a device which causes a heat exchange during the absorption period between said evaporator and a heat radiating part of the thermal power plant, and a device which causes a heat exchange during the absorption period between said generator-absorber and a heat absorbing part of the thermal power plant.
13. In a system in which a continuous absorption apparatus comprising a generator is associated with an absorption apparatus of the intermittent type comprising a generator-absorber, heat-exchange means between parts of both apparatus, said means consisting of a device which causes a heat exchange between said generator of the continuous absorption apparatus and said generator-absorber of the apparatus of the intermittent type during its absorption period.
14. In a system in which a continuous absorption apparatus comprising a generator and heat radiating parts is associated with an absorption apparatus of the intermittent type comprising a generator-absorber and an evaporator, heat-exchange means between parts of both apparatus, said means consisting of a device which causes a heat exchange between said generator-absorber of the absorption apparatus of the intermittent type during its absorption period and said generator of the continuous absorption apparatus, and a device which causes at the same time a heat exchange between said evaporator of the absorption apparatus of the intermittent type and one of said heat radiating parts of the continuous absorption apparatus.
15. In a system in which a continuous absorption apparatus comprising a generator is associated with an absorption apparatus of the intermittent type comprising a generator-absorber,

heat-exchange means between parts of both apparatus, said means being so arranged that said generator of the continuous absorption apparatus is heated by the heat of absorption of said generator-absorber of the absorption apparatus of the intermittent type, a common heating device for the generators of both apparatus, and means for energizing said heating device during the generating period of the absorption apparatus of the intermittent type and for deenergizing the same during the absorption period.

15. In a system for the conversion of heat comprising an intermittently operating absorption apparatus having two units in which vaporous operating medium is developed or is converted into another state of aggregation depending upon the operating periods, and a second heat converter operating on another principle of heat conversion than the said intermittent absorption apparatus, said second heat converter having at

least a heat-absorbing unit in which vaporous operating medium develops and a second radiating unit in which the vaporous operating medium is converted into another state of aggregation, heat exchange means being so arranged between 5 at least one of said units of the heat converter and one of said units of the intermittent absorption apparatus that a demand of heat occurring periodically in the heat converter is met by the conversion of the vaporous operating medium 10 into another state of aggregation in the corresponding unit of the intermittent absorption apparatus and a demand of cold occurring periodically in the heat converter is met by the conversion of the vaporous operating medium into 15 another state of aggregation in the unit of the same intermittent absorption apparatus in heat exchange relation with the heat converter.
